UNITED STATES PATENT OFFICE

HARRIETTE ENSLEY HODGSON, OF NEW YORK, N. Y.

APARTMENT ENLARGER

Application filed June 15, 1928. Serial No. 285,550.

The expense of apartments resulting from modern economic developments bears heavily on the poor and on those of modest means, with the result the greater proportion of individuals and families in centers of population are obliged to put up with quarters which are too small for desirable living conditions. In the case of the poor, crowding is particularly bad, and constitutes a menace to health and general well-being. Among other drawbacks, the lack of privacy is perhaps not the least serious.

The object of this invention is to provide means whereby the usable capacity of a room can be materially increased at very moderate expense. The invention consists in a structure which can be readily set up in any room, and in any desired part of a room, and which can be readily taken down or moved, and which will afford an elevated sleeping or bedroom place with space beneath it available for use either as a low ceiled portion of the living or other room in which the structure is placed, or for bunks supported by the supports which carry the elevated sleeping platform. The main platform is made comparatively narrow, and a platform extension is provided which can be drawn out at night and moved back beneath the main platform for the daytime, so that, when the elevated sleeping space is not in use, the structure need extend over only a small area in the room.

Other features of the invention will become apparent as the specification proceeds.

In the accompanying drawings forming part hereof:

Fig. 1 is a vertical sectional view of the structure in a room, with the structure in its extended condition, the section being taken on the line 1—1 of Fig. 2;

Fig. 2 is a plan view, with portions broken out for economy of space, the walls of the room being in section;

Fig. 3 is a front elevation, with an intermediate portion broken out, the walls of the room being partly indicated in section;

Fig. 4 is a detail sectional view illustrating a connection between the platform or the platform extension and one of the uprights;

Fig. 5 is a detail sectional view illustrating

a connection between one of the uprights and a cross connecting member;

Fig. 6 is a fragmentary elevation of this connection; and

Figs. 7, 8 and 9 are views similar, respectively, to Figs. 1, 2 and 3, illustrating another form of the invention.

The walls of the room are designated 2, the floor 3, and the ceiling 4.

Reference will first be had to Figs. 1-6.

A sleeping platform 5 is supported near, or somewhat above, the mid-height of the room on uprights 6, there being four of these uprights adjacent the corners and an additional intermediate upright or uprights at the rear to divide the span of the platform, which preferably extends substantially the width of the room.

The uprights are rigidly connected by cross-bars 7, which are secured to the uprights by connections which permit the members to be readily taken apart and put together. As illustrated in Figs. 5 and 6, the connections between the uprights and the cross-members may be in the nature of headed projections 8 on the uprights, with which are engaged slotted or notched portions 9 of the bars. The necks of the projections 8 and the sides of the slots 9 are advantageously made straight, so as to prevent any pivoting at the connections. The upper ends of the uprights 6 are detachably connected with the platform 5 as by means of screws 10.

The platform 5 is wide enough to support a bed or cot 11 and a few other articles of furniture, such as a small dresser and a chair. The platform shown in the drawing is just about the width to receive a narrow bed or cot, but naturally a wider platform may be employed if desired.

The platform extension 12 is arranged to slide in and out beneath the platform 5. For this purpose its end edges are shown as being slidably engaged in guides 13 on the under sides of the main platform. For further support of the platform extension when it is drawn out, there are uprights 14 connected at their upper ends with the platform extension. The uprights 14 include members for supporting the forward portion of the platform

extension and an intermediate upright 14^a connected with the rear portion of the extension. When the extension is advanced this upright 14^a serves to support both the extension 12 and the main platform 5 at a region intermediate their ends. When the extension is pushed back, the upright 14^a goes back against the back cross-piece or cross-pieces 7. The uprights 14 and 14^a of the platform extension 12 are provided at their lower ends with wheels 15 to facilitate movement.

The platform extension 12 has a rail or parapet 16 along its front edge, this rail being interrupted at one end, where a flight of ladder steps 17 may be placed. Standards 18 at the front of the platform extension 12 carry a bar 19 near the ceiling, from which to hang a curtain in order to screen the upper sleeping compartment from the rest of the room.

Fig. 3 illustrates the fact that the space beneath the platform 5 is not subtracted from the room as a whole, since there is ample height for articles of furniture, such as a piano 20, a settee 21, or other article, such as a desk, chairs, etc.

When the extension 12 is projected, the uprights 14 are braced by cross-bars 22, which are disconnectably connected with the uprights in a manner similar to that described in connection with the cross-bar 7.

When the extension 12 is drawn out, an upper sleeping room is provided with enough space in it for the few necessary articles of furniture and to permit a person or persons to move about on the extension. In the daytime the extension with its uprights can be pushed back out of the way, so that the whole structure need stand out into the room only slightly further than the width of the platform 5.

The ladder steps 17 can be left connected with the platform extension 12 or they can be disconnected therefrom by virtue of a connection such as illustrated at 23 in Fig. 7.

The ladder steps are designed to have as little projection into the room as may be and at the same time to afford a fair width of step. The flight of steps may be formed of a piece of sheet metal bent into the form of risers and narrow steps, the steps being extended rearward by extensions 24, which can be bent out of openings 25 in the risers. Hand-rails 26 are permanently connected with the upper and lower ends of the flight of steps.

The construction shown in Figs. 7 and 9 is generally similar to that already described. Instead of a movable rear upright 14^a connected with the rear portion of the platform extension 12, it is desirable to provide a stationary front intermediate upright 14^b, which has a roller 27 at its upper end to permit the extension 12 to slide in and out between the upper end of the upright 14^b and the main platform 5, the upright 14^b afford-

ing intermediate support for the front portion of the platform 5 and also for the rear portion of the extension 12 when the latter is drawn forward.

In this instance the space beneath the platform 5 is made use of for bunk beds 28 supported on cross-members 7. Two or more of such bunks can be accommodated, one above another, and at each level there is room for two or more in a horizontal direction. The bunks are separate from each other and removable, so that the number may be varied as desired. Thus, bunks may be placed under one half, more or less, of the length of the platform 5, leaving the remainder of the space beneath the platform free for other uses.

It will be understood that the invention is not limited to the precise details and that other modifications may be devised.

I claim:

1. A structure to be erected in an apartment room to increase the usable capacity thereof, comprising a sleeping platform, supports for supporting the same from the floor of the room at an elevation near or above the mid-height of the room, a platform extension adapted to be drawn out from said platform or to be moved back in superposition therewith, and means for movably supporting said platform extension.

2. A structure to be erected in an apartment room to increase the usable capacity thereof, comprising a sleeping platform, uprights adapted to support the same from the floor in any desired part of a room at an elevation near or above the mid-height of the room, members connecting said uprights, a platform extension adapted to be drawn out from said platform or to be moved back in superposition therewith, uprights movable with said platform extension for supporting the outer part thereof, and members for connecting these uprights with the platform uprights.

3. A structure to be erected in an apartment room to increase the usable capacity thereof, comprising a sleeping platform, uprights adapted to support the same from the floor in any desired part of a room at an elevation near or above the mid-height of the room, members connecting said uprights, a platform extension adapted to be drawn out from said platform or to be moved back in superposition therewith, uprights movable with said platform extension for supporting the outer part thereof, members for connecting these uprights with the platform uprights, detachable connections between the uprights and the platform and platform extension, and detachable rigid connections between the connecting members and the uprights.
